Attest

United States Patent Office.

EDWARD I. ENO, OF SPRINGFIELD, ILLINOIS.

Letters Patent No. 95,214, dated September 28, 1869.

IMPROVEMENT IN CORN-HARVESTERS.

The Schedule referred to in these Letters Patent and making part of the same.

To all whom it may concern:

Be it known that I, EDWARD I. ENO, of Springfield, in the county of Sangamon, and State of Illinois, have invented certain new and useful Improvements in Corn-Harvesters; and do hereby declare that the following is a full, clear, and exact description of the same, reference being had to the accompanying drawing, making a part of this specification, in which—

Figure 1 is a plan view of my improved device;

Figure 2 is a front elevation of the same;

Figure 3 is a vertical cross-section on the lines $z z$ and $y y$ of figs. 1 and 2, respectively; and

Figure 4 is a detached view of the picking-devices.

Letters of like name and kind refer to like parts in each of the figures.

My invention has for its object the plucking or detaching of the ears of corn from the standing stalk; and

It consists in the peculiar construction and arrangement of the several parts thereof, by means of which they co-operate with each other, and enable the whole device to perform the desired office in a superior manner, as is hereinafter fully set forth.

In the annexed drawing—

A represents the axle, having journalled upon its ends the ground-wheels B B, the whole forming the support for the machine.

Secured to and extending backward from the axle is a receiving box, C, having its bottom, c, sloped downward from said axle, so as to cause its contents to fall to the rear, from whence it may be withdrawn by means of a trap, D, formed by hinging the lower half of the rear side of said receiver, c, at its upper edge, so as to permit its bottom edge to swing outward.

The ends of said receiving box extend forward of the axle, and have secured to the inner side of each a bar of iron, E, which is attached at its rear end to the lower side of the axle, and extends forward horizontally to the front of said end-piece D, from whence it curves outward and forward, as seen in figs. 1 and 2, its front end being reduced in width from the commencement of said curve, so as to terminate in a point.

A similar bar or finger-guard, E', is secured to and projects forward from the axle A, at a short distance from and parallel with said guard, its ends being curved outward and forward in an opposite direction, while a third guard, E'', also secured to the axle, extends forward midway between the others, its outer end being curved downward and outward, and the whole so arranged as to embrace and draw together all the stalks of a hill, one set of guards being placed at a suitable distance from the other, so as to enable the machine to operate upon two rows of corn at the same time.

F and F represent the fingers or pickers, resting loosely upon the finger-guards, upon which they are held by means of two pins, z' and z'' , projecting upward from each guard, and fitting into corresponding openings in the lower side of the finger resting thereon, the rear pin z' being of sufficient length to raise said finger somewhat above the guard, and serves as a fulcrum pivot therefor, allowing the finger to rock thereon.

Journalled within suitable bearings, G and G, attached to and extending forward from the axle A, is a shaft, H, to which motion is imparted by means of a pinion, I, secured upon one end thereof, and meshing with the teeth of a female gear, K, attached to and revolving with one of the ground-wheels.

An eccentric, h, is secured upon the shaft H, immediately beneath the rear end of each finger F, and connected therewith by means of a strap, h', passing around said eccentric, and hinged to said finger, so that when the shaft is caused to revolve, the outer end of each finger will be alternately elevated and depressed.

The eccentrics are so adjusted as to cause a corresponding movement of the outer fingers, and an opposite movement of the centre one, so that as the contiguous edges of said guards are sharpened, the effect produced by their operation is similar to that of a double pair of shears.

Immediately in rear of the fingers is a roller, L, journalled within suitable bearings, and connected by an endless band, M, with a similar roller, N, journalled within the front edge of the receiver.

Motion is imparted to said rollers and band by means of a grooved pulley, O, attached to the shaft H, and connected by a cord or belt with a corresponding pulley, n, secured upon the end of the shaft of the roller N.

P represents a shaft, suitably journalled in bearings beneath the finger-guards, and operated by means of a pulley, p, secured to its outer end, and connected with the shaft H, by means of a cord or belt passing around both pulley and shaft.

Secured longitudinally and radially upon the shaft P, are four steel plates, R, the outer edges of which are provided with saw-teeth of the usual form.

As thus described, the device is complete, and its operation is as follows:

The machine is driven forward with the wheels in the hollows, and each set of finger-guards in a line with a row of corn, the stalks of which are gathered together and drawn between the fingers, which, by their peculiar motion, separate the ears from said stalks, and pass them over upon the endless belts, from whence they are conveyed into the receiving-box.

The stalks of corn, after the removal of the ears, are brought in contact with the saw-teeth plates upon the shaft P, which, passing downward and backward, draw said stalks out from between said fingers, and prevent their becoming clogged.

The ears of corn, passing on to the fingers, force those already plucked backward upon the endless bands, which convey them into the receiving-box.

Having thus fully set forth the nature and merits of my invention,

What I claim as new, and desire to secure by Letters Patent, is—

The fingers or pickers F, resting upon the fulcrum pivot z', and operated by means of the eccentrics h, connected to said fingers by the strap h', substantially as herein shown and for the purpose specified.

Also, the finger-guards or gatherers E and E', in combination with the fingers or pickers F, said pick-

ers being constructed and operated substantially as and for the purpose specified.

Also, the shaft P, provided with the radial saw-plates R, and operated by means of the shaft H, in combination with the above-described gathering and picking-devices, substantially as and for the purpose shown.

Also, in combination with said gathering and picking-devices, the endless belt M, operated by means of the rollers L and N, shaft H, and pulleys n and O, substantially as shown and for the purpose specified.

In testimony that I claim the foregoing, I have hereunto set my hand, this 12th day of May, 1869.

EDW. I. ENO.
